UNITED STATES PATENT OFFICE.

WILLIAM F. ROBERTSON, OF CINCINNATI, OHIO.

ROOFING CAP OR SHELL.

SPECIFICATION forming part of Letters Patent No. 673,966, dated May 14, 1901.

Application filed March 20, 1899. Serial No. 709,766. (No model.)

To all whom it may concern:

Be it known that I, WILLIAM F. ROBERTSON, a citizen of the United States, and a resident of the city of Cincinnati, in the county of 5 Hamilton and State of Ohio, have invented certain new and useful Improvements in Roofing Caps or Shells, of which the following is a specification.

The roofing to which my invention is primarily applicable consists of sheets of paper or other textile fabrics.

One of the principal objects of my invention is to provide a cap for holding together sheets of roofing which shall present a long 15 retaining edge along by the edge of the overlapping sheet, and thus the better hold down the roofing-sheet and at the same time present a cap embossed to shed the rain.

Another prominent object of my invention is to provide novel and valuable improvements in roofing-caps—to wit, one or more depressions forming conjointly one depression for preventing the water from standing around the hole through which the nail 25 passes and for conducting the water away therefrom.

The several features of my invention and the various advantages resulting from their use conjointly or otherwise will be apparent 30 from the following description and claims.

In the accompanying drawings, making a part of this application, and in which similar letters of reference indicate corresponding parts, Figure 1 is a plan view of a roofing-cap illustrating my invention and embodying the preferred shape in outline, as 35 hereinafter specified. Fig. 2 is a vertical section of the devices shown in Fig. 1 and taken in the plane of the dotted line 2 2 of Fig. 1. Fig. 3 is a vertical section of the devices shown in Fig. 1 and taken in the plane of the dotted line 3 3 of Fig. 1. Figs. 4, 5, 6, and 7 represent plan views of caps indicating modifications of my invention, as herein- 40 after particularly specified.

A indicates the under sheet of roofing, and B indicates the upper one—viz., that one which overlaps.

C indicates a cap. I so form this cap that 45 it has a straight edge next to the edge of the roofing-sheet that overlaps the sheet below.

In the preferred form of the cap the remainder of the outline is substantially that of a part of a circle, approximately that of a semi-circle. That part of the cap immediately adjoining the edge of the cap is slanting toward its edge, thus forming a border C², so that it draws down flat, or preferably nearly so, when the nail is driven, and the edge will thus always press against the sheet of roofing and not 55 upturn. Within this border the cap is raised or stamped up, presenting, as looked down upon, an embossed surface C³. This embossed surface is provided with one or more depressions, preferably formed as follows: 60 There is a central depression D. Through the metal of this depression the nail E, securing the cap to the roof and for clamping the roofing-sheets to the roof between the cap and the roof, is driven. There are also preferably 65 two depressions D² D² and a third depression D³. Each of these extends from the central depression D to the flat border C². Each depression D² extends from the central depression D to the side of the adjacent corner 70 of the cap and next to the straight edge of the latter, substantially as shown. The depression D³ extends from the central depression D to the middle of the rear side (or edge) of the cap and farthest from the straight 75 edge. The several depressions and their general shape and the form of the embossed or raised parts are well shown in Figs. 1, 2, and 3 of the drawings.

Some of the advantages resulting from my 80 invention are as follows: My invention reduces the number of caps needed to a minimum. The straight edge being everywhere near the edge of the roofing-sheet is utilized for its whole length in holding down the roofing-sheet, and the cap is for its length in close proximity to the edge of the roofing-sheet. A very narrow lap of the roofing-sheet is thus 85 permitted and rendered feasible. The cap holds a long reach of the roofing-sheet down 90 tight. A flat surface in the cap, being central depression D, resting against the roofing-sheet A, is afforded for the nail-head E to rest 95 against. There is no tendency of the edge of the cap to rise up when the nail E is driven 100 to place. (See Figs. 1, 2, and 3.) There are several functions which the ridges perform,

among which may be noted, viz: The ridges constitute bearings and keep water away from the nail-hole should it get under the cap from the edge by any accident. The ridges aid 5 in carrying off the water. The indentation formed to receive the nail will when the roof is painted hold plenty of paint to make it water-tight around the nail-head. Thus the paint settling there seals the opening through 10 the cap around the nail-head, and the water gathering in this depression will flow out along in the depressions D^2 , D^2 , and D^3 . The depressions are so arranged that the cap may be nailed on in any position and water entering 15 any of the depressions would be carried off through another depression or depressions. Some of the water flowing down the roof will enter the depression D^3 and flow into depression D . Thence it is conducted down the roof 20 by the gutter or leader depressions D^2 D^2 . These central indentations enable shorter nails to be used than would be the case were the indentation absent. In regard to drainage 25 it will be observed that my cap presents a minimum edge for the water to follow.

In Figs. 4 to 6, inclusive, of the drawings I have shown various modified forms of the cap. All of these embody the feature of the straight edge adjacent to that edge of the upper roofing-sheet which lies upon the lower roofing-sheet, and this straight edge of the cap is substantially parallel to such edge of the upper roofing-sheet. All of these caps possess the feature of a raised or central portion 35 surrounded by a flat border with or without ribs or depressions.

The cap shown in Fig. 5 is rectangular. In the cap Fig. 5 there is present a central depression D for the nail, and connected therewith are the two canal or leader depressions 40 D^2 D^2 D^2 D^2 , each leading to points, respectively, near to its adjacent corner of the cap, but to one side thereof, as hereinafter indicated.

Fig. 6 presents a picture of a cap of a triangular form. The cap shown in Fig. 6 has depressions similar to those shown in the cap represented in Figs. 1, 2, and 3.

Fig. 4 shows a cap similar in outline to that 50 shown in Fig. 1, but from which depressions have been omitted.

Under the general feature or features of my invention details may be varied; but a construction substantially such as the specific 55 one shown in Figs. 1, 2, and 3 is the one which I much prefer.

Inasmuch as a large amount of the sheet-roofing now applied to roofs consists of very thin paper liable to turn up at the overlapping 60 edge under various influences, the advantage of my invention is in that connection especially apparent.

In relation to the modification shown in Fig. 7 it is to be noted that round plain embossed caps have been in use heretofore, and the figure is intended to show the application 65 to the rounded cap of those features of my in-

vention heretofore described as ribs and gutters.

It is to be understood that by the term 70 "straight" as applied in this specification to the edge I mean an edge substantially straight. Embossing the cap draws the straight edge in a little. So, also, minute indentations or serrations of the edge would 75 not affect the general character of the straight edge I have invented and would, though not desirable, be included within the scope of my invention.

What I claim as new and of my invention, 80 and desire to secure by Letters Patent, is—

1. A roofing-cap having a straight edge adapted to rest upon the upper sheet of roofing, near that edge of the latter which overlaps the under sheet of roofing, and to lie substantially parallel to the latter, a border for the cap, and the part within the border being raised, the latter being provided with a central depression and one or more depressions 85 extending from there to the borders of the cap, substantially as and for the purposes specified.

2. A roofing-cap having a straight edge adapted to rest upon the upper sheet of roofing, near that edge of the latter which overlaps the under sheet of roofing, and to lie substantially parallel to the latter, the border of the cap being substantially as specified, and the part within the border being raised, the 95 outline of the cap, except the straight edge 100 being semicircular, substantially as and for the purposes specified.

3. A roofing-cap having a straight edge adapted to rest upon the upper sheet of roofing, near that edge of the latter which overlaps the under sheet of roofing, and to lie substantially parallel to the latter, the border of the cap being formed substantially as set forth, and the part within the border being raised, the outline of the cap, except the 105 straight edge, being semicircular, and the cap being provided with a central depression and depressions extending from there to the borders of the cap, substantially as and for the purposes specified. 115

4. A roofing-cap having a straight edge adapted to rest upon the upper sheet of roofing, near that edge of the latter which overlaps the under sheet of roofing, and to lie substantially parallel to the latter, the border of the cap being formed substantially as described, and the part within the border being raised, the outline of the cap, except the straight edge, being semicircular, and the cap being provided with a central depression 120 D , and the two depressions extending thence to points respectively near the opposite corners of the cap, where the straight edge thereof meets the semicircular portion thereof, and another depression extending from the central depression to about the middle of the semicircular edge thereof, substantially as and for the purposes specified. 125 130

5. An embossed roofing-cap having a

straight edge adapted to rest upon the upper sheet of roofing near that edge of the latter which overlaps the under sheet of roofing, and to lie substantially parallel to the latter, the 5 embossed portion of the cap being provided with one or more depressions, substantially as and for the purposes specified.

6. An embossed roofing - cap having a straight edge adapted to rest upon the upper 10 sheet of roofing near that edge of the latter which overlaps the under sheet of roofing, and to lie substantially parallel to the latter, the embossed portion being provided with a central depression, one or more depressions extending from there to the borders of the cap, substantially as and for the purposes 15 specified.

substantially as and for the purposes specified.

7. An embossed roofing - cap having a straight edge adapted to rest upon the upper sheet of roofing substantially as described, 20 the outline of the cap, except the straight edge, being semicircular, the cap being provided with a central depression and depressions extending from there to the borders of the cap, substantially as and for the purposes 25 specified.
